UNITED STATES PATENT OFFICE.

JOSEPH A. STANSBURY, OF BALDWINSVILLE, NEW YORK.

IMPROVEMENT IN PUMPS.

Specification forming part of Letters Patent No. **56,627**, dated July 24, 1866.

To all whom it may concern:

Be it known that I, J. A. STANSBURY, of Baldwinsville, in the county of Onondaga and State of New York, have invented certain new and useful Improvements in Direct-Acting Force-Pumps; and I do hereby declare that the following is a full and exact description thereof, reference being had to the accompanying drawings, making part of this specification.

Figure 1 is a side elevation of my improved pump; Fig. 2, a central vertical section; Fig. 3, a plan with the top of the case removed to show the interior arrangement; Fig. 4, a diagram showing the arrangement of the abutment and the guide for turning the wings of the piston; Fig. 5, a diagram, in perspective, of the guide and piston-wings; Fig. 6, a perspective view of a portion of the hub of the piston-wings and the lower flange in which it works.

Like letters of reference indicate corresponding parts in all the figures.

My improvement belongs to that class where the pump proper is placed below the surface of the water, and where the column is raised by revolving wings acting directly upon the body of liquid admitted within the pump-case.

As represented in the drawings, the case is made up of a body, A, and a cover, B, which are suitably bolted or screwed together. The body of the case is provided with an induction-port, *a*, and a water-passage, *b*. With the cover or top is connected an elevating-tube, C, extending to the top of the well.

The body and cover of the case are provided with rims *c c* inside, Fig. 2, within which rests a hub, D, that receives motion by a shaft, E, extending to the top of the well, and operated by any suitable means. The hub has a flange, *d*, projecting out from between the rims, and centrally through this flange and through the hub passes loosely a horizontal shaft, *f*, to the ends of which are riveted or otherwise suitably secured wings *g g*, which, when standing vertically, just fill the cross area of the water-passage *b*.

In order to allow the wings to fit closely to the peripheries of the rims *c c* the flange *d* is notched flush with said rims, as shown at *h h*, Figs. 1 and 6. The wings are set at right an-

gles relatively—that is, when one stands vertical the other is horizontal.

On the inside of the case, at a suitable position, is secured a guide, G, which may be made of wire or rod, as shown, or may be cast as a part of the case, or formed in any other suitable manner. It projects inward, laterally, just sufficiently for the ends of the wings to strike and ride thereon as they go around, as indicated in Fig. 5, and its length is such as to allow the turning of the wings in the proper position for carrying the water in the case around and discharging it, as will presently be described. At the extremities the guide is turned downward, as shown at *i i*.

At the end of the guide on which the wings first strike is a projection or stop, *k*, and also a small spring, *l*, for first receiving the concussion of the wings and turning them into the proper position for riding on the guide.

At the proper position next the induction-port is an abutment made up of two parts, *m* and *n*, the former stationary, but the latter jointed by means of an arm, *o*, and pivot *p*, so as to rise and fall over the stationary part. The jointed part is also provided with a cam-face, *q*, inclined upward and backward to allow the wings to pass edgewise between, as will presently be explained.

The action of the pump thus arranged will be easily understood. The wings revolving in the direction of the arrows carry the water in front and discharge it through the tube C. At the moment the lower edge of either wing strikes the spring *l* and stop *k* it is turned from a vertical to a horizontal position, and, striking flatwise on the guide G, is steadily held and carried around to the opposite end of the guide in the same position. The same action that turns this wing into the horizontal position also turns the opposite wing into the vertical position, since both are attached to the same shaft *f*, and this turns freely in the hub D. Thus the wings turn into the vertical position directly after passing the induction-port, and carry the water bodily before them, and turn into the horizontal position just before reaching the abutment; and this action is infallible unless the pump becomes deranged, for one wing cannot turn without the other.

In the act of passing the abutment it will be

perceived that the latter yields or opens for the purpose, and this action is produced by the edge of the wings striking the inclined cam-face *g*. There is thus but little escape, while there is no danger of breakage.

The spring *l* serves to break the shock of the concussion of the wings, and also serves to commence the turning motion of said wings before striking an unyielding stop.

This pump is valuable for all ordinary uses, but especially so when large power is required or when liquid having much sediment is to be raised—for instance, in breweries.

What I claim as my invention, and desire to secure by Letters Patent, is—

1. The combination of the right-angled wings *g g*, attached to and turning with the same shaft, and the guide *G*, when said parts are used in connection with a pump, substantially as herein specified.

2. The abutment made up of the parts *m* and *n*, in combination with the wings *g g*, operating substantially as herein set forth.

3. The spring *l*, in combination, with the wings *g g* and guide *G*, operating substantially as specified.

4. In combination with the wings *g g* and the shaft *f*, the hub *D*, provided with the flange *d*, substantially as described.

5. The arrangement, as a whole, consisting of the wings *g g*, guide *G*, abutment *m n*, hub *D*, and spring *l*.

In witness whereof I have hereunto signed my name in the presence of two subscribing witnesses.

JOSEPH A. STANSBURY.
